UNITED STATES PATENT OFFICE.

ROBERT L. SMITH AND JAMES WARHURST, JR., OF BERWYN, ILLINOIS.

GAS-FIXTURE.

SPECIFICATION forming part of Letters Patent No. 735,837, dated August 11, 1903.

Application filed March 20, 1903. Serial No. 148,674. (No model.)

To all whom it may concern:

Be it known that we, ROBERT L. SMITH and JAMES WARHURST, Jr., citizens of the United States of America, residing at Berwyn, in the county of Cook and State of Illinois, have invented certain new and useful Improvements in Gas-Fixtures, of which the following is a specification.

Our invention relates to certain new and useful improvements in gas-fixtures; and its object is to produce a device of this class which shall have certain advantages of construction and operation, which will appear fully and at large in the course of this specification.

To this end our invention consists in certain novel features of construction, which are clearly illustrated in the accompanying drawings and described in this specification.

In the aforesaid drawings, Figure 1 is a front elevation of our improved device. Fig. 2 is a side elevation showing the parts in a different position. Fig. 3 is a section in the line 3 3 of Fig. 2 looking in the direction of the arrow. Fig. 4 is a section in the line 4 4 of Fig. 2, and Fig. 5 is a section in the line 5 5 of Fig. 1, looking downward.

Referring now to the drawings, A is the end of the gas-pipe to which the fixture is secured.

To said pipe A is secured a fitting B, provided with two outlets b and b'. The outlet b' is controlled by a stop-cock b², having at its outer end an arm b³, to which are secured chains b⁴, so that the stop-cock may be turned from below. The opening b is directly opposite the pipe A and connected therewith by a by-pass b⁵, which passes around the stop-cock b² and that portion of the fitting in which it is seated. To the said opening b of the fitting B is screwed a straight vertical pipe C, having at its lower end a T-coupling C' and burners C², each controlled by a suitable stop-cock. It is obvious, of course, that any other structure may be substituted for this plain T structure, this form being shown merely for the purpose of illustration.

In the opening b' of the fitting B is pivoted a pipe or tube D, having an ordinary gas connection with said opening after the manner of any pivoted or jointed gas-pipe, and to the opposite end of this pipe D is pivoted a series of pipes jointed together at their ends

and indicated in the drawings by D' D² D³ D⁴, respectively. To the pivot of the pipe D upon the fitting B is also pivoted a plate or rod of metal E, to the opposite end of which is pivoted a series of bars or plates E' E² E³ E⁴, said bars E' E² E³ crossing the pipes D' D² D³ at the centers of the rods and pipes and being pivoted to said pipes, respectively, so as to form with said pipes an ordinary lazy-tongs construction. To the lower end of the lazy-tongs structure and connected with the joint e upon the end of the pipe D⁴ is a pipe F. Said pipe F extends a slight distance above the lower end of the lazy-tongs in the form of a nipple f⁸, and it is there provided with a collar f', running on the pipe C. The pipe C is likewise provided near its lower end with a similar collar f', running on the pipe F. To the lower end of the pipe F is secured a T-coupling or other fitting F', having burners F².

The operation of this much of the device will now be apparent. When gas is admitted to the pipe A, it passes through the fitting B into the tube C and to the burner C², where it can be burned. When it is desired to light the burners F², one of the chains b⁴ is pulled, so as to turn the stop-cock b² and admit gas through the opening b' to the lazy-tongs structure, through which it will pass to the pipe F and thence to the burner F². The pipe F is obviously vertically movable, so that the entire lower fixture can be vertically moved at will. This type of fixture is particularly desirable for libraries and the like, where it can be placed over a table, the upper set of burners being kept lighted to light the room and the lower set being drawn down when it is desired to light the table, but being pushed up out of the way at will.

In order to secure the movable pipe F and the fixtures attached thereto in any desired vertical position, a lever G, having a circular hole of somewhat larger diameter than the pipe C, is pivoted to a bracket f⁴, secured to the upper end of the pipe F, with the circular hole surrounding the pipe C. To the opposite end of the lever G is connected a rod G', guided by a collar g on the pipe F and terminating at its lower end in a knob g'. The operation of this locking device is quite obvious. The weight of the rod G' holds the

lever normally in the position shown in Fig. 1, wherein the sharp edges of the hole in the lever are wedged upon the opposite sides of the pipe and so prevent downward movement 5 of the lower fixtures. When it is desired to lower the pipe F and fixtures attached thereto, the knob g' is pushed up, releasing the lever from this wedged position upon the pipe and permitting free vertical movement. 10 Releasing the knob will lock the parts in a perfectly obvious manner.

We realize that considerable variations are possible in the details of this construction without departing from the spirit of the invention, and we therefore do not intend to 15 limit ourselves to the specific form herein shown and described, except as pointed out in the claims.

We claim as new and desire to secure by Letters Patent—

1. The combination, in a device of the class described, and with a supply-pipe extended to form a guide, of a stop-cock in the supply-pipe having a by-pass connecting the portions of said supply-pipe on opposite sides of 25 the cock, a series of jointed tubular arms connected with the eduction side of the stop-cock and guided longitudinally of the supply-pipe, a second pipe parallel with the supply-pipe forming a continuation of said tubular 30

arms guided upon the supply-pipe to move substantially parallel therewith and burners arranged at the ends of the extended supply-pipe and the second pipe, respectively.

2. In a device of the class described, the 35 combination with a supply-pipe extended to form a guide, of a series of jointed tubular arms connected with and opening into the supply-pipe and guided longitudinally of the supply-pipe, a second pipe parallel to and 40 beside the supply-pipe, forming a continuation of the tubular arms, guided to move substantially parallel therewith, and burners on the ends of said two pipes, substantially as described.

In witness whereof we have signed the above application for Letters Patent, at Chicago, in the county of Cook and State of Illinois, this 17th day of March, A. D. 1903.
